UNITED STATES PATENT OFFICE.

HENRY F. BRUNKENHOFER, OF GALVESTON, TEXAS.

MAIL-BAG-HANDLING APPARATUS.

1,078,768.

Specification of Letters Patent. Patented Nov. 18, 1913.

Application filed March 27, 1913. Serial No. 757,190.

To all whom it may concern:

Be it known that I, HENRY F. BRUNKENHOFER, a citizen of the United States, residing at Galveston, in the county of Galveston and State of Texas, have invented certain new and useful Improvements in Mail-Bag-Handling Apparatus, of which the following is a specification.

My invention relates to a mail-bag handling apparatus, and more specifically to apparatus designed to practically simultaneously deliver and receive bags or pouches containing mail or other matter, to and from a moving train or body.

15 Among the objects of the invention is the provision of improved apparatus of this type that will safely handle the bags, that is simple in construction, that will prove durable in use, and that can be manufactured at moderate cost.

Another object of the invention is to provide the mechanism of such construction that it may be adjusted to the most desirable positions when not in use.

25 A further object is to provide means for receiving the mail bags discharged from a car, that will protect the contained or received bags and contents thereof against rain, water or fire.

30 Numerous other objects will appear hereinafter from the description following taken in connection with the accompanying drawings, wherein the preferred embodiment is shown.

35 In said drawings:—Figure 1 is a plan view of the apparatus, showing the same projected from a car, the latter being shown partially and in section; Fig. 2 is a side elevation of the catching or supporting member employed; Fig. 3 is an elevation taken

40 at right angles to Fig. 1 showing the catching or supporting means in projected position; Fig. 4 is a view of the same parts as Fig. 3, but showing the parts in retracted or

45 folded position against the car; Fig. 5 is an enlarged plan view of the catching or supporting member and of parts supporting the same and carried thereby; Fig. 6 is a sectional view on the line 6—6 of Fig. 5; Fig. 7

50 is an elevation illustrating the means arranged along a siding or railway track for receiving the discharged bags or pouches;

Fig. 8 is a perspective view of the means for supporting a bag or pouch along a siding; Fig. 9 is an elevation partly broken

away showing the type of bag adapted to be caught by the apparatus carried by the car; Fig. 10 is an elevation partly broken away showing the type of bag adapted to be supported by and discharged from the car; and Fig. 11 is an elevation of a modified form of means for receiving the bags discharged from a car.

Throughout the various views of the drawings, like reference characters designate like or similar parts.

Referring specifically to the drawings, 1 designates fragmentarily, a car across the doorway of which is supported a rod or bar 2 by means of suitable brackets such as 3. For the purpose of rendering this bar and parts supported thereby removable when desired, as for transferring it to the opposite side of the car, the same is removably supported and one way of accomplishing this end is by providing alining openings in one bracket 3 and the bar, through which may be removably inserted a fastening pin member 4. The rod 2 is round or annular in cross section and thereon is slidably and turnably mounted by means of a hub 5, a projecting arm 6 which may be reinforced or strengthened by a rib 7. This projecting arm is adapted at times, to be projected from the car or extend at right angles thereto as shown in Fig. 3, so as to maintain parts carried thereby in proper position and the arm in said position is rigidly supported by the engagement of a brace arm 8 extending from the hub entering a notch provided in a bracket 9 bifurcated as at 10. For the purpose of adjusting the projecting arm, a handle such as 11 is provided and is connected rigidly to the hub 5.

Upon the projecting arm 6 is mounted to slide longitudinally thereof, a catching or supporting member generally designated 12. This member on opposite sides of the arm 6 terminates in a plurality of outwardly diverging arms 13 which are adapted to guide the flexible member of a caught bag or pouch to a slot 14 defined at the junction of the arms 13 to the central portion of the catching or supporting member 12.

The mail-bags to be caught are preferably of the type shown in Fig. 9 and consist of the bag or pouch 15 having connected thereto a flexible fastening member such as a cord 16 which is fastened to a plurality of spaced apart enlargements provided by the 110

balls 17 suitably fastened to the cord 16. The bag to be caught is supported by the engagement of one of the enlargements 17 with spaced apart lugs 18 extending from 5 a striker arm 19 which is supported in any suitable manner as by means of a post 20 arranged along the railway track. As the car moves past the striker arm, the adjacent arms 13 extend on opposite sides of the 10 fastening member of the bag 15 and guide the same to the adjacent slot 14. The end wall of the slot 14 engages the cord 16 and positively moves the same and accordingly the bag 15 off of the lugs 18, the bag being 15 supported and held by the arms 13 at the slot 14 by reason of the fact that the adjacent ball 17 rests above and on the arms. As is well known, a car vibrates considerably as it travels, and for this reason a plurality of the balls 17 are provided so that 20 the arms 13 can catch the fastening member of bag 15 from various heights. It might be stated that the catching or supporting member 12 is fastened to the projecting arm 6 against lateral movement by reason of the 25 fact that a T-shaped slot 21 engaging the supporting arm is provided on the catching or supporting member 12.

On opposite sides of the projecting arm 6 30 extend vertically in the catching or supporting member, slots designated 22 over which are arranged to extend the outer ends 23 of a slidable lock member in the form of a toothed rack 24. It will be noted that the 35 upper face of the ends 23 are flat or plane.

The mail-bag to be delivered from the car 40 may be of the type shown in Fig. 10, and therein the bag proper is designated 25 and has a suitable fastening member 26 shown 45 in the form of a link. When this bag 25 is fastened in position to be discharged from the car, its link 26 extends through the proper slot 22 and the end 23 adjacent said slot extends through the link and supports 50 the link in the manner shown best in Figs. 5 and 6.

Upon the catching or supporting member 12 is pivoted to suitable lugs 27, a gear member 28 provided with teeth adapted to mesh 55 with those of the rack 24. This gear member is shown in the form of a segment and is provided with a projecting member or arm 30. For the purpose of normally maintaining the arm 30 in vertical position, and 60 the ends 23 over the slots 22, a return spring 31 is provided and is fastened to the arm 30 and to one lug 27. When the parts are folded against the car as in Fig. 4, it may be desirous to fold arm 30 flat to a plane substantially parallel with that of the arms 13, and to this end the lug 27 to which spring 65 31 is attached, is of such length as to render the spring inactive for return purposes when folded to the parallel plane referred 70 to. Arm 30 is arranged so that in the travel

of the car past striker arm 19, said arm 30 will strike the arm 19 which will accordingly shift arm 30, and through the intermeshing of the gear teeth thereon and those of the rack 24, slide the rack 24 to such extent as to move the end 23 in engagement with the link 26, from engagement with said link whereupon the bag 25 previously supported will fall by gravity therefrom and thus be discharged from the car. 75

Troughs 32 are provided to catch the bags discharged as described, which are best shown in Fig. 7. These troughs lead to and enter suitable chutes 33 and preferably have inclined side walls 34 which converge between the chutes. Said chutes 33 lead to a suitable receptacle 35 which is preferably provided with a door 36 locked at 37, by means of which access to the interior of receptacle 35 may be had in order to remove the mail-bags contained therein. The troughs, chutes and receptacle are supported in any suitable manner as by means of posts 38 and brace rods 39, as shown in the drawings, the receptacle 35 it will be noticed, is arranged above the ground. This form of receiving means will effectively shield the mail bags or pouches against the entrance of water, such as rain water, and fires which frequently occur from burning grass along 85 a railway track. 90

In Fig. 11 a modified form of receiving means is provided and which might be desirable in some instances, inasmuch as it can be more cheaply manufactured than the form shown in Fig. 7. In this figure 40 designates the receptacle, 41 the troughs, and 42 the support post; said parts 40, 41 and 42 being the equivalent of the parts 35, 34 and 38 respectively, of Fig. 7. 100

Means is provided whereby the catching or supporting member may be slid longitudinally of the projecting arm relatively to the car to facilitate the fastening of a bag thereon and to remove a caught bag from the slots 14. To this end a pull member or rod 43 is pivoted at 44 to the catching or supporting member. At the inner end of the pull member 43 extend at right angles thereto arms designated 45 and 46, the former of which may engage an opening or slot 47 provided in the projecting arm or more specifically its handle 11. When the arm 45 is in engagement with the slot 45' as shown in Fig. 3, the catching or supporting arm is projected from the car and in position to catch a mail-bag and deliver the mail-bag supported thereby. This projected position is also well illustrated in Fig. 1. Pull member 43 may be raised vertically to disengage 110 the arm 45 and slot 45' so that the member 43 may be pulled to slide the catching or supporting member longitudinally of the projecting arm. In order to maintain the rod 43 in position always accessible from 115 120 125 130

within the car, the same is mounted in and extends through a vertically elongated slot 47 provided in an arm 48 rising from hub 5.

As before stated, the apparatus just described is adapted to be folded or moved to position where it will be against and vertically relatively to the car. Prior to shifting the parts to this position, arm 45 is disengaged from slot 45' and the pull member 43 supported in the slot of arm 48. Thereupon arm 11 is depressed which accordingly moves the arm 8 from engagement with the bracket 9; so that the apparatus can then be slid longitudinally of bar or rod 2 to the desired extent. Through further depression of arm 11, the apparatus is brought to the vertical position. In such position the parts are fastened through the engagement of the arm 46 with a hook 49 of a bracket 50 fastened 20 to the car at the doorway thereof. To guard against sliding of the catching or supporting member off of projecting arm 6 in case of damage to any of the parts, as by breakage or injury to pull member 43, an abutting member 51 is fastened in any suitable manner to the projecting arm 6. This member as shown consists of a cotter pin fastened in a suitable opening in the projecting arm and whose head projects or extends above the 30 arm.

In briefly reviewing the operation of the parts, it will be stated that the parts when not in use are supported vertically against the side of the car as in Fig. 4, through the engagement of arm 46 with the hook 49. In order to bring these parts to position so that the mail-bag may be supported therefrom by the proper end 23, the arm 46 is disengaged from the hook 49 and thereupon arm 40 11 is depressed until the supporting arm is brought to a substantially horizontal position, whereupon it is slid to the proper extent longitudinally of rod 2 to position where arm 8 is opposite the slot of bracket 45 10, whereupon arm 11 is released and the projecting arm will be supported in this position by the engagement of arm 8 with the bracket. In this position the catching or supporting member will be located adjacent 50 the door of the car and in position best facilitating the fastening of a bag to be discharged thereon. After fastening said bag, rod 43 is pushed outwardly in order to arrange the catching or supporting member in projected position. Upon such position being gained, arm 45 is entered in slot 46, whereby the catching or supporting member 12 is rigidly fastened in such position. As the train or car moves or travels, the bag 60 such as 15 is caught in the proper slot 14 by the engagement of the slot with the flexible member 16 and enlargements 17. As to the bag to be discharged, arm 30 during such movement or travel of the car strikes 65 the striker arm 19 which accordingly shifts

the gear member 28 which through the intermeshing of its teeth with those of the rack or lock member 24, slides the lock member so that the end 23 will disengage the link 26, whereupon the bag 25 will fall by gravity 70 onto the chutes 32 or 41 according to the form of receiving means employed, and therefrom into the receptacle. In the case of the receiving means employed as shown in Figs. 1 and 7, the bags or pouches pass 75 immediately of the receptacles and trough through the chute 33. After arm 30 moves past striker arm 19, return spring 31 restores the same to normal position where the lock member or more specifically the 80 ends 23 thereof, extend over the openings 22. Upon removing the caught bag from the catching or supporting member 12, rod 43 is pulled inwardly to bring the member 12 to a better position for removal of the bag. 85 As to the bag delivered to the receptacle 35, the same may be readily removed upon unlocking the door 36.

Many changes in the details of construction of the device described herein, may be 90 made within the spirit and scope of the appended claims, and hence are reserved.

Having thus described my said invention, what I claim as new and desire to secure by Letters Patent is:—

1. In handling apparatus, a projecting member, a support member slidable thereon, a shifting member for said support member, an arm on said shifting member, said support provided with a slot receiving said arm, 100 a guide member, said guide member provided with an elongated slot through which said shifting member passes.

2. In handling apparatus, a support member, a slidable lock member thereon provided with teeth, a gear member provided with teeth in mesh with said teeth, and means engageable with said gear member to shift the same and accordingly the lock member.

3. In handling apparatus, a support member provided with a slot, a slidable lock member mounted to extend over said slot, teeth on said lock member, a gear member having teeth in mesh with said teeth, an arm on said gear member, a return spring operatively connected to said arm, in combination with a striker member engageable by said arm.

4. A mail bag handling apparatus including a projecting member comprising an arm having a reinforcing rod formed longitudinally thereon, a bag supporting member conforming to the configuration of said projecting member and slidably arranged therewith, means for operating said supporting member on said projecting member, a gear plate slidably mounted on said support, a gear member meshing with said plate, and a handle carried by said gear member for the purpose specified.

5. A mail bag handling apparatus including a bar, a hub rotatably and slidably arranged on said bar, an arm radiating from said hub, a longitudinally extending rib 5 formed on said arm, a bag supporting member slidably arranged on said arm, a pull member, the one end of which is pivotally engaged with said supporting member for operating the latter, arms formed on the 10 opposite end of said pull member, outwardly diverging arms formed on said support, said support member provided with a pair of openings one of which is arranged on each side of said arms, a rack bar slidably mounted on said support member over said openings, the opposite ends of said bar being smooth and adapted for engagement with the mail bag, a segmental gear meshing with said rack bar, and a handle associated with 15 20 said gear for facilitating the operation thereof.
6. A mail bag handling apparatus including a bar, a hub rotatably and slidably arranged on said bar, an arm radiating from said hub, a longitudinally extending rib 25

formed on said arm, a bag supporting member slidably arranged on said arm, said member provided with a pair of openings therein, a pull member the one end of which is pivotally engaged with said support member, for operating the latter, arms formed on the opposite end of said pull member, a rack bar slidably mounted on said support member over said openings, the opposite ends of said bar being smooth and adapted for engagement with the mail bag, a segmental gear meshing with said rack bar for operating the same on said support member, a handle extending from said segmental gear, a hook carried by the upper end of said handle, and a spring the one end of which is in engagement with said hook and the opposite end engaging with said support member for the purpose specified.

In testimony whereof I affix my signature in presence of two witnesses.

HENRY F. BRUNKENHOEFER.
